CLAIM

The ornamental design for a laser chassis as shown and described.

DESCRIPTION

1.1 Perspective view

1.2 Perspective view

1.3 Front view

1.4 Back view

1.5 Left view

1.6 Right view

1.7 Top view

1.8 Bottom view

The characteristic features is the overall shape of the product. The figure 1.1 best shows the main points of the design. The broken lines depict portions of the laser chassis that form no part of the claimed design.

1 Claim, 8 Drawing Sheets
